UNITED STATES PATENT OFFICE.

WILLIAM ACKROYD, OF BIRKENSHAW, AND WILLIAM BEST, OF MORLEY,
ENGLAND.

APPARATUS FOR LIGHTING MINERS' SAFETY-LAMPS.

SPECIFICATION forming part of Letters Patent No. 550,469, dated November 26, 1895.

Application filed January 11, 1895. Serial No. 534,511. (No model.)

To all whom it may concern:

Be it known that we, WILLIAM ACKROYD, residing at Birkenshaw, and WILLIAM BEST, residing at Morley, in the county of York, 5 England, subjects of the Queen of Great Britain and Ireland, have invented certain Improvements in Apparatus for Lighting Miners' Safety - Lamps, of which the following is a specification.

10 The object of our invention is to construct apparatus for lighting miners' safety-lamps through the medium of a spark caused by the broken contact of two electrical conductors in such a manner that the parts employed therewith are few and of simple construction and the generation of an external electric spark is practically impossible, while at the same time the light of the lamp is not diminished by the lighting apparatus and misfiring 20 is entirely obviated.

In making practical experiments with lamps and lighting apparatus invented we have found serious defects which render the said invention unreliable.

25 According to our invention, and with reference to the vertical section shown in the accompanying drawing, we mount the stationary carbon A in a box A', which box is attached to the side of the wick-tube B, so that 30 the upper surface of the said carbon A is at or below the level of the wick-tube B.

The movable carbon C is mounted on a conductor-spring D at the same side of the lamp as that of the stationary carbon A, the said 35 conductor-spring D being firmly connected to an insulated cover B', situated on the wick-tube B, in such a manner that the carbon C is free to advance into contact with the stationary carbon A, situated at the side of the wick 40 of the lamp.

An insulated tube M passes up through the oil-chamber G, and a conducting-rod N is fitted within the insulated tube M in such a manner that on its being pressed upward it 45 comes against the under side of the spring D, causing such spring to advance toward the wick-tube B, and thereby moving the carbon C into contact with the carbon A. On removing the upward pressure from the rod N 50 the spring D recedes or moves away from the

wick-tube B, carrying with it the carbon C, and thus breaking the contact between the two carbons.

On a table T, of non-conducting material, we mount a circular receptacle or ring P for 55 the reception of the lamp. Within this ring P and on the table T a cylindrical conductor R is provided, which is connected by a wire R' to one pole of an electric generator or accumulator by means of a terminal R², and 60 within the conductor R a conductor S is situated, being insulated from the conductor R by means of the insulating material R³.

The conductor S is connected by a wire S' to the opposite pole of the generator or accumulator by means of a terminal S², and the said conductor S is kept up to a certain height by means of the spring S³. At the upper part of the conductor S we provide insulating material S⁵, which acts as a guard in preventing 70 a short circuit being formed between the upper ends of the conductors R and S.

When it is desired to light a lamp fitted with apparatus constructed according to our invention, the said lamp is placed within the 75 ring P and pressed downward, when the conductor S first comes in contact with the lamp-bottom G, and on the continued downward pressure the conductor S descends, allowing the rod N to come in contact with the conductor R, which action advances the carbon C into contact with the carbon A, when an electric circuit is completed, the current passing by way of the wire S', terminal S², conductor S, oil-chamber G, wick-tube B, carbon 80 A, carbon C, spring D, rod N, conductor R, terminal R², and wire R'. The passing current immediately warms the oil in the wick B', which emits vapor, and on releasing the downward pressure on the lamp the two carbons A and C are suddenly separated, thus 85 breaking the circuit and causing a flash to take place, which instantly lights the already-heated wick B'.

In lighting lamps above ground the apparatus shown can be employed without any 95 guard to prevent sparks from the generator or accumulator coming into contact with the surrounding air; but when used below ground, where an explosive gas may exist, the table 100

T forms the lid of an air-tight or explosion-proof box in which the generator or accumulator is inclosed.

In the latter arrangement should sparks be made at the generator or accumulator no danger will be caused to the "mine," as the surrounding air is securely cut off from contact with the interior of the box.

By having the carbon A at or below the upper surface of the wick-tube B, as above described, the light is not diminished, as is the case with a carbon projecting above the level of the wick-tube, and by having the two carbons A and C situated at one and the same side of the wick-tube B the necessity of the moving carbon C crossing the wick B' is dispensed with, and thus the danger of misfiring by the wick B' coming between the two carbons A and C and preventing contact is entirely obviated.

By actuating the carbon C through the medium of a conductor-rod N, passing through the lamp-bottom G, as above described, the danger of non-lighting by the lamp-bottom screwing up untrue and the production of an external spark caused by a broken circuit is completely removed.

We claim as our invention—

1. In a miner's safety lamp, the combination of the wick and wick tube, the electric lighting means consisting of two carbons, one attached to the wick tube and the other attached to a conductor spring, both carbons being at or below the level of the wick tube, the conductor spring being actuated by the conducting rod which passes through the lamp by way of the insulated tube, the electric current being supplied from a generator or accumulator substantially as set forth.
2. In a miner's safety lamp, the combination of the contact carbons A, and C, arranged adjacent to and at or below the level of the wick, the spring D, which is firmly connected to the insulated cover B², the conducting rod N, passing by way of an insulated tube M, and projecting through the lamp bottom, in such a manner that on the conducting rod N, being raised by one of a pair of conductors, which are the two poles of an electric circuit, the circuit is completed by the

carbons A, and C, coming into contact, the current of electricity passing by way of the body of the lamp G, the wick tube B, carbon A, carbon C, spring D, and conducting rod N, and when the two carbons A, and C, are brought apart, the contact is broken and a flash takes place which lights the wick of the lamp, substantially as set forth.

3. The combination with the oil chamber G, of the lamp and the movable insulated conducting rod N, of a ring P, located on a table T, to receive the lamp, a cylindrical conductor R, within the ring P, and in electrical connection with one pole of the electric generator, an insulated and vertically movable conductor S, located within the conductor R, and in connection with the opposite pole of the electric generator, and a spring S³, for holding the end of the conductor S, raised above the conductor R, whereby on insertion into the ring P, the oil chamber makes contact with the conductor S, and on the depression of the latter the movable conductor N, of the lamp makes contact with the conductor R, and completes the circuit, the circuit being broken and the wick lighted by removal of the lamp as set forth.

4. The combination in a miner's lamp of two spark points adjacent to the wick, a spring for supporting one of such spark points, an insulated conducting rod passing vertically through the base of the lamp for actuating the spring and spark point, a base into which the bottom of the lamp is placed, a central spring rod and electric circuit connection for making contact with the base of the lamp and an insulated cylinder to which the other electric circuit wire is connected and with which the insulated conducting rod comes into contact as the lamp is set into its base for closing the circuit and lighting the lamp as it is removed, substantially as set forth.

In witness whereof we have hereunto set our hands in the presence of two witnesses.

WM. ACKROYD.
WILLIAM BEST.
